US0D1023116S

(12) **United States Design Patent** (10) **Patent No.:** **US D1,023,116 S**
(45) **Date of Patent:** **** Apr. 16, 2024**

(54) **PHOTOGRAPHING SUPPORT**

(71) **Applicant:** **SHENZHEN HAOHUALIANHE TECHNOLOGY CO., LTD.,**
Guangdong (CN)

(72) **Inventor:** **Weihao Chen**, Guangdong (CN)

(73) **Assignee:** **SHENZHEN HAOHUALIANHE TECHNOLOGY CO., LTD.,** Shenzhen
(CN)

(**) **Term:** **15 Years**

(21) **Appl. No.:** **29/847,399**

(22) **Filed:** **Jul. 25, 2022**

(30) **Foreign Application Priority Data**

Jan. 25, 2022 (CN) 202230053229.7

(51) **LOC (14) Cl.** **16-05**

(52) **U.S. Cl.**

USPC **D16/244; D16/243**

(57) **CLAIM**

The ornamental design for a photographing support, as
shown and described.

DESCRIPTION

FIG. 1 is a perspective view of a photographing support;
FIG. 2 is a front view thereof;
FIG. 3 is a rear view thereof;
FIG. 4 is a left view thereof;
FIG. 5 is a right view thereof;
FIG. 6 is a top view thereof;
FIG. 7 is a bottom view thereof; and,
FIG. 8 is a perspective view thereof in a folded configura-
tion.

1 Claim, 8 Drawing Sheets
